DISPOSABLE PUMP CASSETTE FOR MEDICAL INFUSION PUMPS

Sydney Hudspith, San Diego, Calif., assignor to Imed Corporation, San Diego, Calif.

Filed Aug. 6, 1973, Ser. No. 386,041

Term of patent 14 years

Int. Cl. D24—02

U.S. Cl. D83—1 F

FIG. 4

FIG. 3

FIG. 1 is a front isometric view of a disposable pump cassette for medical infusion pumps showing my new design;

FIG. 2 is a rear isometric view thereof;

FIG. 3 is a front elevational view thereof;

FIG. 4 is a rear elevational view thereof.

I claim:

The ornamental design for a disposable pump cassette for medical infusion pumps, as shown.
